UNITED STATES PATENT OFFICE.

GEORGE CALVERT THOMPSON, OF DARIEN, GEORGIA, ASSIGNOR TO HIMSELF,
JAMES L. FOSTER, AND WILLIAM S. MALLARD, ALL OF SAME PLACE.

CAR-COUPING.

SPECIFICATION forming part of Letters Patent No. 331,218, dated November 24, 1885.

Application filed July 31, 1885. Serial No. 173,198. (No model.)

To all whom it may concern:

Be it known that I, GEORGE CALVERT THOMPSON, a citizen of the United States, residing at Darien, in the county of McIntosh 5 and State of Georgia, have invented a new and useful Improvement in Car-Couplings, of which the following is a description.

This invention is an improvement in car-couplings; and it consists in certain novel 10 constructions, combinations, and arrangements of parts, as will be hereinafter first fully described, and then pointed out in the claims.

In the drawings, Figure 1 is a perspective view of one end of a car provided with my 15 improvement. Fig. 2 is a longitudinal section drawn through the draw-bar. Fig. 3 is a cross-section of the draw-head, and Fig. 4 is a detail perspective view of the coupling-hook.

20 The draw-head A may be attached to the car in the usual manner. It is formed with a flaring mouth, A', the mortise A², and the slot A³, the latter being cut through the top wall, as shown. The under side of the forward end of the top wall is formed with the curved portion a and the stop portion a', inclining forward and downwardly from the said 25 curved portion.

In the upper face of the lower side of the 30 draw-head I form a socket or depression, a², in which rests the point of the coupling-hook B. This coupling-hook B is pivoted on a pin, C, below the curve a and stop a', and concentrically with the arc in which said curve a 35 is described. The upper forward end of the hook is formed with a curve, b, and a straight stop portion, b', carried forward from the said curved part b. These parts b and b' can be formed with or fit closely against the parts a a' of 40 the draw-head, as most clearly shown in Fig.

2. The front end, b², of the coupling-hook is beveled or inclined rearwardly from its upper to its under side, and operates to guide an approaching link downward toward the point 45 of said hook, so it may readily pass thereunder into engagement with the securing shoulder b³. The point of the hook, it will be seen, is rounded to fit the socket a², and to permit the easy passage of the link under it in the

operation of the device. Immediately in rear 50 of this shoulder b³ the under side of the hook or its shank is formed with a recess, b⁴, and at its rear end such hook has a depending portion, b⁵, terminating in the straight beveled end G of shank, which bevel receives the 55 weight of the hook, relieving the point thereof of all strain.

In operation, the recess b⁴ allows free play of the link while the cars are in motion, and enables it to be raised or lowered to couple 60 with a higher or lower draw-head, and the projection b⁵, by bearing on the rear cross-bar of the link, when such link is pushed entirely in, holds such link in horizontal position to couple with draw-heads of equal or 65 nearly equal height—that is, slightly higher or lower, for when the link strikes the flared mouth A' above or below the mortise A² the beveled edge will guide the coupling-hook down or up to the mortise and effect an entrance. A spring, D, is secured at its forward 70 end to the draw-head, and, bearing against the rear end of the coupling-hook, operates to hold such hook in the position shown in Fig.

2. On the end of the car, above and on opposite sides of the line of the draw-head, I secure 75 guides E E, preferably anti-friction rollers, as shown. A chain or cord, F, connects with the coupling-hook at f, and extends thence upward between the guides E, where it connects with connections or branch cords F' and F' F². The connection F' extends upward, and is held by a keeper, f', in position to be reached from the top of the car, and the connections F² extend laterally over guides f² to 80 the side of the car. By pulling on these cords the rear end of the coupling-hook may be elevated and the link released by a person on either side or the top of the car.

85 My invention, it will be seen, is simple, and 90 provides a construction which will not easily get out of order.

By means of the several guides provided for the hook-operating devices such parts may be used with but slight friction, and consequently 95 with ease and facility.

Having thus described my invention, what I claim as new is—

1. A car-coupling hook pivotally supported at its forward end, and beveled or inclined rearwardly at such end from its upper to its lower side, and having a securing shoulder, 5 b^3 , a recess, b^4 , in its under side in rear of such shoulder, and a depending projection, b^5 , at its rear end, substantially as and for the purposes specified.

2. The combination, in a car-coupling, of 10 the draw-head having a mouth, A' , mortise A^2 , and the slot A^3 , and having the under side

of its top wall curved at a and extended forward in a straight line or stop, a' , and the coupling-hook pivoted below the said curved and stop portions of the stop-wall, and having 15 its upper forward end curved and flattened at b b' correspondingly to said curved and stop portions a and a' , substantially as set forth.

GEORGE CALVERT THOMPSON.
